(57) **CLAIM**

The ornamental design for a table as shown and described.

DESCRIPTION

FIGS. 1-8 illustrate a first embodiment of a table design in which

FIG. 1 is a perspective view thereof;

FIG. 2 is front elevation thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof, and

FIG. 8 is a cross-sectional view of the table of FIG. 2 taken along line 8-8.

FIGS. 9-16 illustrate a second embodiment of a table design in which

FIG. 9 is a perspective view thereof;

FIG. 10 is front elevation thereof;

FIG. 11 is a rear elevation view thereof;

FIG. 12 is a right elevation view thereof;

FIG. 13 is a left elevation view thereof;

FIG. 14 is a top plan view thereof;

FIG. 15 is a bottom plan view thereof; and

FIG. 16 is a cross-sectional view of the table of FIG. 10 taken along line 16-16.

FIGS. 17-24 illustrate a third embodiment of a table design in which

FIG. 17 is a perspective view thereof;

FIG. 18 is front elevation thereof;

FIG. 19 is a rear elevation view thereof;

FIG. 20 is a right elevation view thereof;

FIG. 21 is a left elevation view thereof;

FIG. 22 is a top plan view thereof;

FIG. 23 is a bottom plan view thereof; and

FIG. 24 is a cross-sectional view of the table of FIG. 18 taken along line 24-24.

FIGS. 25-32 illustrate a fourth embodiment of a table design in which

FIG. 25 is a perspective view thereof;

(Continued)

FIG. 29 is a left elevation view thereof;
 FIG. 30 is a top plan view thereof;
 FIG. 31 is a bottom plan view thereof; and,
 FIG. 32 is a cross-sectional view of the table of FIG. 26
 taken along line 32-32.

The dashed broken lines in the figures are for the purpose of illustrating environmental structure and form no part of the claimed design. The symbolic break lines in the figures convey that the appearance of any portion between the symbolic break lines forms no part of the claimed design. The dotted lines with arrows indicate where cross-sectional views have been taken and form no part of the claimed design. The cross sectional views are to illustrate the external surface contour of the Table. The broken lines and line hatching in these views are not intended to illustrate the internal construction of the table and form no part of the claimed design.
